US00D961458S

(12) **United States Design Patent** (10) **Patent No.:** **US D961,458 S**
(45) **Date of Patent:** **** Aug. 23, 2022**

(54) **ELECTRIC SCOOTER**

(71) Applicant: **SUPERSOCO INTELLIGENT TECHNOLOGY (SHANGHAI) CO., LTD.**, Shanghai (CN)

(72) Inventor: **Yuxian Xie**, Shanghai (CN)

(73) Assignee: **SUPERSOCO INTELLIGENT TECHNOLOGY (SHANGHAI) CO., LTD.**, Shanghai (CN)

(**) Term: **15 Years**

(21) Appl. No.: **29/762,363**

(22) Filed: **Dec. 16, 2020**

(30) **Foreign Application Priority Data**

Dec. 9, 2020 (EM) 008313092

(51) **LOC (13) Cl.** **12-11**

(52) **U.S. Cl.**

USPC **D12/110**
